UNITED STATES PATENT OFFICE.

CHARLES EDWARD CHAFFIN, OF NEW YORK, N. Y., ASSIGNOR TO THE GENERAL ENGINEERING COMPANY, OF NEW YORK, N. Y., A CORPORATION OF UTAH.

VALVE-ACTUATING MECHANISM.

Application filed November 19, 1920. Serial No. 425,259.

To all whom it may concern:

Be it known that I, CHARLES EDWARD CHAFFIN, a citizen of the United States, residing at New York, New York, have invented certain new and useful Improvements in Valve-Actuating Mechanism, of which the following is a description.

This invention relates to improvements in valve actuating mechanism adapted for use in connection with various styles and types of valves, and the like, and has for its object to provide mechanism of this character which is simple in construction, and positive and efficient in operation.

More particularly the invention relates to valve actuating mechanism which is automatically actuated, and by means of which the shifting of the valve is effected in a sudden and rapid manner, thus increasing the efficiency of the valve by decreasing the interval of time during which the valve moves from one position to another. Furthermore, the actuating mechanism is so constructed as to provide for periodical pauses, of a desired interval of time, between successive shifting movements of the valve.

In the accompanying drawings, forming part of this application, wherein are shown several preferred embodiments of the invention for the purpose of illustrating the principle thereof,

Figure 1 is a view in side elevation, parts being broken away, of a valve actuating mechanism embodying my invention, the same being shown in connection with a tank outlet valve.

Figure 2 is a front view of the apparatus shown in Figure 1, parts being broken away;

Figures 3 and 4 are side and front views, respectively, of a slightly modified form of valve actuating mechanism shown in connection with a valve for controlling the flow of fluid through a conduit;

Figures 5 and 6 are side and front views showing a further modified form of valve actuating mechanism in connection with a three-way valve;

Figures 7 and 8 are views similar to Figures 5 and 6 showing a slightly different construction of the valve actuating mechanism;

Figure 9 is a plan view showing a still further modification of valve actuating mechanism embodying the invention;

Figure 10 is a sectional view taken on the line X—X of Figure 9, and

Figure 11 is a front view of the apparatus shown in Figure 9.

Referring to Figures 1 and 2 of the drawings, 1 indicates the lower portion of a tank having a discharge nozzle 2 at its lower end the opening and closing of which is controlled by a ball valve 3 operatively connected by arms 4 to one end of a lever 5 pivotally supported upon a bracket 6 secured to the tank. The other end of the lever 5 carries a weight 7 which serves to maintain the valve normally in its closed position. An adjustable actuating member 8 has one of its ends operatively connected to the lever 5 and its other connected to a housing 9 provided with vertical registering slots 10 formed in its side walls through which extends a shaft 11 supported in bearings 12 carried by brackets 13 mounted upon a suitable frame 14 which is shown as being supported upon the tank 1. The shaft 11 is rotated at a uniform rate in one direction in any suitable manner, as for example, by means of a driven worm 15 meshing with a worm gear 16 fixed to the shaft.

Rotatably mounted upon the shaft 11, and extending through the slots 10 of the housing 9, is a sleeve 17 carrying a cam 18 positioned within the housing 9 and adapted to engage a block 19 adjustably supported within the housing by means of a vertically adjustable screw 20 adapted to be rotated by a hand wheel 21 to vary the position of the block within the housing. A weighted arm 22 carried by the sleeve 17, is secured thereto so as to rotate therewith as by means of a bolt 23 engaging any one of a plurality of holes 24 formed in a quadrant 25 secured to the sleeve. The weighted arm 22 will normally be suspended from the shaft 11 in a vertically downward position and the cam 18 will be out of engagement with the block 19, thus permitting the housing 9 to occupy its normal position with the upper ends of the slots 10 engaging the sleeve 17, as shown. When the housing 9 is in this position the ball valve 3 closes the discharge nozzle 2. Fixed to the shaft 11 adjacent the weighted arm 22 is a disc 26 carrying a horizontally-extending pin 27 adapted, as the disc rotates, to engage the normally suspended weighted arm 22 and cause it, together with

the sleeve 17 and cam 18, to rotate in unison with the shaft 11 whereby the weighted arm will be raised to a vertically upward position, it being understood that 5 the shaft 11 and disc 26 rotate in a clockwise direction as seen in Figure 1. As the disc continues to rotate the weighted arm will be carried beyond the vertical and will then move downwardly, due to the action 10 of gravity, the sleeve 17 to which it is secured rotating about the shaft 11. During this movement of the arm and sleeve, relative to the shaft 11, the cam 18 will engage the block 19 thus raising the housing 9 with 15 respect to the shaft 11, which movement is permitted by reason of the vertical slots 10 through which the shaft extends. As the housing is thus raised by the cam, the lever 5 will be actuated by the member 8 to 20 cause the ball valve 3 to be moved away from the discharge nozzle 2 whereupon the contents of the tank will be discharged. As the cam 18 moves out of engagement with the block 19 the housing 9 and the lever 5 are restored to their normal positions by the 25 action of gravity, thereby causing the ball valve 3 to again close the discharge nozzle 2. The interval of time that the discharge nozzle is opened by the downward movement 30 of the valve may be varied by varying the position of the adjustable block 19 within the housing 9 or by varying the point of connection between the actuating member 8 and the lever 7. The interval of time that the 35 discharge nozzle is opened may also be varied by varying the point of connection between the weighted arm 22 and the quadrant 25. If, for example, the bolt 23, which connects these members, engages the right 40 hand hole of the series of holes 24 in the quadrant, as seen in Figure 1, the arm 22 will begin its downward movement before the cam 18 engages the block 19 and therefore the block 19 will be raised to open the 45 valve solely during the downward movement of the arm. If, on the other hand, the bolt 23 engages the left hand hole of the series, the cam 18 will engage the block 19 during 50 the upward movement of the arm 22 and will remain in engagement with the block during a portion of the downward movement of the arm. In order to permit the weighted arm 22 to come to rest without 55 shock as it reaches its normal or suspended position, it is preferably provided with a dash pot 28 adapted to receive a plunger 29 carried by the disc 26. The arm will remain in its normal suspended position until the pin 27 secured to the disc 26, which 60 continues to rotate at a uniform rate, is again brought into engagement with the weighted arm 22, whereupon the operation is repeated.

Referring to Figures 3 and 4, 30 indicates a frame upon which is supported a shaft 31

having a gear wheel 32 secured thereto adapted to engage a driven gear wheel, not shown, whereby uniform rotation of the shaft is effected. Rotatably mounted upon the shaft is a sleeve 33 to which a weighted arm 34 is secured by a set screw 34'. Fixed to the sleeve, preferably integral therewith, is a cam 35. A disc 36 secured to the shaft carries a pin 37 adapted to engage the weighted arm and raise it from its normally suspended position to a vertically upright position, as explained above in connection with Figures 1 and 2. As the arm passes its vertically upright position it moves rapidly downwardly, owing to the action of gravity, until it engages the pin 37' carried by the disc 36 and during such movement the cam 35 is caused to engage and depress one end of a pivotally supported lever 38 which is operatively connected to the valve stem 39 of a valve within a valve casing 40 interposed in a conduit 41, whereby the valve is shifted from its normal to its alternate position. As the arm 34 engages the pin 37' before the cam 35 moves out of engagement with the lever 38, the lever will remain depressed until the disc 36 rotates a sufficient distance to permit the cam to become disengaged from the lever. A tension spring 42 secured to the other end of the lever 38 returns the valve to its normal position, when the cam 35 moves out of engagement with the lever, and maintains the valve in such position until the weighted arm is again actuated to cause the cam to actuate the lever. As the arm 34 is rotatably mounted upon the sleeve 33, being secured in position with respect thereto by the set screw 34', the position of the arm relative to the cam 35 may be varied to vary the length of time that the cam will engage the lever 38, whereby the interval of time that the valve 40 is maintained in its alternate position may be varied.

Referring to Figures 5 and 6, the valve actuating mechanism is shown in connection with a three-way valve having two spring pressed valves 43 and 44 adapted to be actuated by means of a pivotally mounted lever 45 alternately engaging the valve stems. A spring pressed rod 46, secured to the lever 45 normally holds the lever in engagement with the stem of the valve 43 to hold the same open, the valve 44 being normally closed. As the weighted arm 47 moves downwardly from its vertical position, to which it is raised by the disc 48 as above described, the cam 49, which moves in unison with the arm, engages the lever 45, moving it out of engagement with the stem of valve 43 and into engagement with the stem of valve 44, whereupon valve 44 will be opened and valve 43 will be permitted to close. The weighted arm is shown as being provided with a cushioning device 50 adapt-

ed to engage a stop 51 carried by the disc 48 while the cam 49 is still in engagement with the lever 45 whereby the valve 44 will be held open until the disc rotates a sufficient 5 distance to permit the cam to move out of engagement with the lever. As soon as the cam is disengaged from the lever the spring pressed rod 46 moves the lever to its normal position thus opening the valve 43 and permitting the valve 44 to close. As the disc continues to rotate the weighted arm is again raised to its vertical position by the pin 52 and the above described operation is repeated. The position of the arm 47 relative to the arm 49 may be varied to vary the interval of time that the valve 44 is held open in the manner above explained in connection with Figures 3 and 4. In order to permit the members to be adjusted with accuracy a micrometer adjustment 47' is provided upon the arm 47 adapted to co-act with a lug 49' on the sleeve which carries the cam 49.

The valve actuating mechanism shown in Figures 7 and 8 comprises a weighted arm 53 and a cam 54 rotatably mounted upon a uniformly driven shaft 55 to which is secured an arm 56 adapted to engage the weighted arm 53 and raise it to its vertical 30 position from which it falls by gravity to its normally suspended position. During the upward movement of the weighted arm the operative face 57 of the cam 54 engages the lever 58 and forces it into engagement with the stem of valve 59 thus opening the valve 59 and permitting the valve 60 to close. When the weighted arm moves beyond the vertical position it falls, by gravity, and during this movement the cam is carried out of engagement with the lever 58 which is thereupon moved by the spring pressed rod 61 to its normal position in engagement with the stem of valve 60, thus opening such valve and permitting the valve 59 to close. The 40 position of the arm 53 relative to the position of the cam 54 may be varied to vary the interval of time that the valves are opened or closed, as above set forth in connection with Figures 3, 4, 5 and 6.

50 As shown in Figures 9, 10 and 11, the uniformly driven shaft 62 carries a bevel gear 63 meshing with bevel gears 64 and 65 which are rotated in opposite directions, and which carry pins 66 and 67 adapted 55 to co-act with weighted arms 68 and 69 rotatably mounted upon a shaft 70. The arms are provided at their lower ends with studs 71 and 72 adapted to engage arms 73 and 74 secured to a shaft 75 carrying 60 a crank 76 operatively connected to a valve actuating arm 77. As the bevel gears 64 and 65 rotate they alternately raise the weighted arms 68 and 69 to their vertical positions from which they fall by gravity 65 in the manner above explained. As the

weighted arms fall the arms 73 and 74 are alternately engaged by the studs 71 and 72 to effect a back and forth rocking movement of the shaft 75 and crank 76, and of the valve actuating arm 77, whereby the 70 valve is alternately shifted from one position to the other. The bevel gear 64 is preferably provided with a series of holes 78 any one of which is adapted to receive and hold the pin 66, and by varying the 75 position of the pin upon the bevel gear the interval between the alternate shifting movements of the valve may be varied. If desired, the bevel gear 65 may also be provided with a similar series of holes to permit of the adjustment of the pin 67 with respect thereto.

From the above it will be seen that the valve actuating mechanism is so constructed as to provide for a sudden and rapid shifting of the valve or the like from one position to another and that there will be a pause of any desired interval of time, between the successive movements of the same. The number of times that the valve 90 is shifted during any period of time, will of course depend upon the speed of rotation of the shaft which carries the member for raising the weighted arm from its normally suspended position, and such speed of rotation may be varied as desired.

It will of course be understood that valve actuating mechanism embodying the invention may be employed for actuating valves, cocks or pilot devices, of types other than 100 those shown and described.

While the invention is illustrated and described in connection with several preferred embodiments thereof, it will be understood that I do not intend to limit myself to the specific embodiment shown, but that I intend to cover the invention broadly in whatever form its principles may be employed.

Having thus described my invention, I 110 claim:—

1. In mechanism of the character described, completely rotatable valve-actuating means, and means for moving the same through a portion of its travel, said valve actuating means being movable through the 115 remaining portion of its travel independently of said moving means.

2. In mechanism of the character described, completely rotatable valve-actuating means, and uniformly rotating means for moving the same through a portion of its travel, said valve actuating means being movable through the remaining portion 120 of its travel independently of said moving means.

3. In mechanism of the character described, completely rotatable valve-actuating means, and means for moving the same through a portion of its travel, said valve actuating means being movable through the 125 130

remaining portion of its travel independently of said moving means.

4. In mechanism of the character described, completely rotatable valve actuating means, and uniformly rotating means for moving the same through a portion of its travel, said valve actuating means being movable through the remaining portion of its travel independently of said moving means and at a higher rate of speed than the speed of said moving means.

5. In mechanism of the character described, completely rotatable valve actuating means movable by gravity through a portion of its travel, and means for moving the same through the remaining portion of its travel.

6. In a mechanism of the class described, valve actuating means mounted for complete rotary movement about a horizontal axis, and means for moving said actuating means from its lowermost to its uppermost position, said actuating means being movable from its uppermost position to its lowermost position independently of said moving means.

7. In mechanism of the character described, a shaft, valve actuating means rotatably supported thereon and normally occupying a suspended position with respect thereto, and means adapted to engage said actuating means and move the same upwardly about said shaft, said actuating means moving downwardly to its normal position independently of said moving means.

8. In mechanism of the character described, a shaft, valve actuating means rotatably supported thereon, including a rotatable weighted arm normally extending downwardly with respect to said shaft, and means free from connection with said arm for rotating it upwardly to carry it past a vertically upright position whereby it will return by gravity to its normal position.

9. In mechanism of the character described, a rotatable shaft, valve actuating means including a weighted arm rotatably supported thereon, and means rotatable with said shaft adapted to engage said arm and move it through a portion of its travel, said arm moving through the remaining portion of its travel independently of said moving means.

10. In mechanism of the character described, a rotatable shaft, a weighted arm rotatably supported thereon, a valve actuating member movable with said arm, a member secured to said shaft and rotatable

therewith, and means carried by said member adapted to engage said arm and move it through a portion of its travel, said arm moving through the remaining portion of its travel independently of said arm engaging means.

11. In mechanism of the character described, a rotatable shaft, a weighted arm rotatably supported thereon and normally suspended therefrom, a valve actuating member rotatable with said arm, and means rotatable with said shaft for periodically engaging said arm and moving it to an upright vertical position, said arm moving to its suspended position independently of said moving means and remaining in such position until it is again engaged thereby.

12. In mechanism of the character described, a shaft, valve actuating means rotatably supported thereon including a valve actuating member and a weighted arm, and means rotatable with said shaft for controlling the movement of said valve actuating means.

13. In mechanism of the character described, a shaft, valve actuating means rotatably supported thereon including a valve actuating member and a weighted arm, and means rotatable with said shaft for controlling the movement of said valve actuating means, said valve actuating member and said weighted arm being adjustable relative to one another.

14. In mechanism of the character described, a shaft, valve actuating means rotatably supported thereon including a valve actuating member and a weighted arm, and means rotatable with said shaft adapted to co-act with said weighted arm to control the operation of said valve actuating means and to maintain said valve actuating member in operative position during an interval of time.

15. In mechanism of the character described, a shaft, valve actuating means rotatably supported thereon including a valve actuating member and a weighted arm, and means rotatable with said shaft adapted to co-act with said weighted arm to control the operation of said valve actuating means and to maintain said valve actuating member in operative position during an interval of time, said weighted arm being adjustable relative to said valve actuating member whereby said interval of time may be varied.

In testimony whereof I have affixed my signature to this specification.

CHARLES EDWARD CHAFFIN.
